UNITED STATES PATENT OFFICE.

WILLIAM L. BREATH, OF BROOKLYN, NEW YORK.

INTERNAL-COMBUSTION ENGINE.

1,133,531.

Specification of Letters Patent. Patented Mar. 30, 1915.

Application filed August 20, 1910. Serial No. 578,205.

To all whom it may concern:

Be it known that I, WILLIAM L. BREATH, a citizen of the United States, residing at Brooklyn, in the county of Kings and State 5 of New York, have invented a new and useful Internal-Combustion Engine, of which the following is a specification.

My invention relates to gas engines and the like, and involves the construction of 10 the larger and heavier parts of such engines of sheet metal, preferably stamped or drawn, as the exigencies of the case require, in contradistinction to following the present practice of making such parts of castings. The 15 change in structure proposed not only cheapens the cost of construction, but materially saves in weight. The parts to be made of sheet metal particularly contemplated herein are the cylinders, base, crank-shaft 20 bracket and base cover.

In the drawings which form a part hereof: Figure 1 is a vertical transverse section of a gas engine constructed in accordance with the principles of my invention. Fig. 25 2 is a detail of a modification of a part of said engine. Fig. 3 is a vertical longitudinal section of the engine shown in Fig. 1.

Like reference characters designate like 30 parts throughout the several views.

Referring to the drawings, I have therein shown by way of exemplification, a four cylinder engine in which the crank-shaft has been designated A, said shaft being journaled in the crank-shaft bearing bracket B. 35 This bracket, which it will be observed, carries substantially all of the crank-shaft bearings, differs in form from the devices of this character as heretofore constructed which have usually been castings, in that it 40 is made of sheet metal, and furthermore, has the supporting flanges C thereof disposed preferably considerably above the crank-shaft, so that the shaft is actually hung or suspended from above, whereas in engines as heretofore constructed, the shaft has been substantially level with said flanges, or with the points of attachment of the bracket to its base. By reason of 45 the change in question the material of which the bracket is composed is normally under tension and is not in flexure, as in the usual design. The thin sheet metal which it is proposed to use in the construction of this part would signal fail in rigidity unless 50 advantage was taken of its great tensional

strength, and the construction employed is adapted to effectually utilize this quality of the metal, the bracket in question virtually constituting a cradle for the shaft. In Fig. 2 I have shown a modification of this member, and of the manner of attaching the same to the base, whereby the same object may be attained, but the form illustrated in Fig. 1 is preferred. It will be observed that the bracket B is a single structure comprising the flanges c along the two sides by which the bracket is secured to the supporting structure, the cross-arms in which the bearings are carried, and connecting webs c' between the cross-arms and extending to 60 the flanges c, the cross-arms and webs being channeled to impart stiffness thereto. This unitary structure affords great rigidity and strength to withstand the strains to which various parts of it are successively subjected by the force of the repeated explosions in the various cylinders. Another portion of the engine which I contemplate making of stamped metal is the base D, said 65 base being provided with a flange E around the bottom thereof to match the flanges of the bearing bracket to which it may be bolted, as well as to the supporting framing 70 of the engine.

The upper side of the base has preferably 75 a series of openings therein, one for each cylinder, said openings having curved flanges therearound as at F. The cylinders may be drawn sheet metal tubes, having at 80 the bottoms thereof curved flanges G adapted to neatly fit inside the matching flanges of the base, the cylinder tubes being inserted into position from the bottom and being then welded securely to said base. The purpose of this construction is to bring the engine reactions directly on the metal flanges, and not on the welds; and it will be observed that the construction in question is 85 peculiarly advantageous, in that the metal parts are not weakened as they would be if screw threads, or the like, had been employed, but are actually strengthened by the flange construction utilized. Furthermore 90 owing to the tapering fit of the flanges on the cylinder and base, the cylinder is readily centered when mounting it upon the base. The cylinder heads H may, if desired, be castings, and are preferably fused to the 95 top of the cylinder tubes at I. Each cylinder head may carry inlet and exhaust valves 100 105

and the usual spark plug. The water jacket J is also preferably made of stamped sheet metal, the bottom of which may be flanged as at K and shaped to accurately conform 5 to the base to which it is fused. At the bottom of the jacket are flanged openings, one for each cylinder, the flanges of which openings are slightly tapered as shown at I to fit corresponding tapers on the cylinder 10 heads. For greater surety, as the water jacket will usually be made of light gage metal, a ring L is forced onto the tapered flange before this joint is fused. Each jacket J is contoured near its bottom to 15 form a double curve in the metal which allows for expansion and contraction due to heat; and the nature of this double curve is such that it forms in effect a substantially annular or ring-like diaphragm M, the general plane of which is substantially normal to the axis of the cylinder. This diaphragm is coned or flexed in one direction or the other as the metal of the jacket expands or contracts. In the exemplification shown, the 20 ring like diaphragm is not circular but is approximately ellipsoidal. An oil cover N made of stamped sheet metal, completes the closure around the crank-shaft.

From the foregoing it will be seen that 30 nearly all of the essential parts of the engine may be made of steel metal, advantage being taken of the very high tensile strength which material of this description may possess; while at the same time the weight of

the structure may be reduced by the use of 35 such material substantially to a minimum.

Having described my invention, I claim:

1. In an internal combustion engine, a supporting structure, a crank shaft, and a supporting bracket therefor, said bracket 40 being a unitary structure of sheet metal consisting of two side flanges by which it is secured to the supporting structure, a plurality of cross-arms each carrying a bearing for the shaft, said cross-arms being spaced 45 apart to permit the play of the cranks therebetween and connecting webs between said cross-arms extending to the respective side flanges, said cross-arms and the connecting web being channeled for the purpose set 50 forth.

2. In an engine, a cylinder of sheet metal, a base therefor, and a crank-shaft driven by said cylinder, the base being apertured for the reception of said cylinder and the cylinder projecting through said aperture and being flanged for engagement with the side of the base adjacent said crank shaft, the reactive effort of the cylinder being carried by said flange, said flange being tapered 55 and thereby aiding in centering the cylinder in the base aperture within which it is disposed.

WM. L. BREATH.
